UNITED STATES PATENT OFFICE.

HOWARD BRUCE, OF BALTIMORE, MARYLAND, ASSIGNOR TO THE BARTLETT HAYWARD COMPANY, OF BALTIMORE, MARYLAND, A CORPORATION OF MARYLAND.

APPARATUS FOR MANUFACTURING COAL-GAS.

1,144,977.

Specification of Letters Patent. Patented June 29, 1915.

Application filed January 7, 1914. Serial No. 810,723.

To all whom it may concern:

Be it known that I, HOWARD BRUCE, a citizen of the United States, residing at Baltimore, in the State of Maryland, have invented certain new and useful Improvements in Apparatus for Manufacturing Coal-Gas, of which the following is a specification.

This invention relates to improvements in gas retorts and has for its object to provide improved means for adjustably sustaining the stand pipes and for adjustably bracing the mouth pieces of the retorts with respect to each other whereby to provide for the relative shifting of the parts by expansion and contraction.

With the above, and other objects in view, the invention is illustrated in the accompanying drawing wherein,—

Figure 1, shows a series of vertically-arranged retorts in front elevation,—each vertical row of retorts being provided with a stand-pipe constructed and arranged according to the invention. Fig. 2, shows a vertical series of retorts and the stand-pipe connected therewith partly in vertical section and part in side elevation. Fig. 3, shows an enlarged vertical sectional detail through the adjusting devices for the standpipes and also the improved braces for the retort mouthpieces the section being taken on the line 3—3 of Fig. 2. Fig. 4, illustrates a horizontal cross-sectional detail on an enlarged scale of the sustaining means for the upper ends of the standpipes,—the section being taken on the line 4—4 of Fig. 1. Fig. 5, shows an enlarged vertical section through the slip joint at the upper end of the standpipe.

Referring to the drawings, the numerals, 9, designates a vertical series of retorts, set in the usual or any preferred manner and having mouthpieces, 10, which project from the retort proper. Each mouthpiece has a door, 11, which may be opened for charging and discharging purposes in the usual manner, and also, each mouthpiece has a side passage, 12, for connection with a standpipe, presently to be explained.

The mouthpieces are arranged in vertical rows,—one directly above another and each mouthpiece, with the exception of the uppermost one, has an upper socket, 13, and a lower socket 14, in vertical alinement. A stem, 15, has its upper end seated in the

lower socket, 14, of one mouthpiece and its lower end entered in the upper socket, 13, of the mouthpiece next below, and between the two ends each stem is exteriorly threaded so that a nut, 16, may be screwed thereon. 60 Each nut, 16, is seated on the upper socket, 13, of the mouthpiece below it so that by simply turning the nut the stem may be raised sufficiently to brace and support the mouthpiece above it from the mouthpiece below it. A bracket, 17, is carried on a horizontal beam, 18, below the lowermost mouthpiece and a threaded post 19, having a nut, 20, thereon forms the lowermost of the vertically-aligned mouthpiece supports. 65 70 A standpipe, 21, extends vertically at one side of each vertical row of retort-mouthpieces and each standpipe has a series of lateral openings, 22, which are disposed in horizontal planes, one above another, so as 75 to connect with the several side passages, 12, of the mouthpieces, as clearly shown in Fig. 4. It will therefore be seen that one standpipe has as many side openings or passages as there are retort mouthpieces in a vertical 80 row to one side of it, and that all the retorts of a vertical row have a separate and independent connection with the same standpipe,—the connection from one retort to the standpipe being entirely separate and independent of the connection to the same standpipe from any other retort in the same vertical row.

Each standpipe depends below the lowermost mouthpiece of the vertical row of retorts and has its lower end dipping into a tar seal pot, 23, which has an outlet, 24, that leads to a tar cistern.

Between the lowermost retort and the tar seal pot, 23, each standpipe has an exterior 95 circumferential flange or collar, 25. In the present instance these flanges or collars are located above the horizontal beam, 18, so that bearing brackets, 26, may be seated on said beam and sustain adjustable posts, 27, 100 whose upper ends enter suitable sockets in the standpipe flanges or collars. The adjustment in this instance is effected as in the case of the mouthpiece supports, by means of adjusting nuts, 28, which seat on the 105 bearing brackets, 26.

The standpipes proper extend straight up from the seal pots, 23, and said straight portion passes all of the lateral openings, 22, from the several retorts in a vertical row. 110

At the upper end each vertical standpipe has a flared end section, 29, into which the lower end of a union pipe, 30, has a slip connection. Each union pipe or connection, 30, is rigidly sustained from a vertical beam, 31, by means of suitable brackets or plates, 32, and each of said sections, 30, has a top cap, 33, and a front cap, 34, both of which may be removed for purposes of cleaning. 5 10 15 10 A perforated pipe, 35, is also located in each section, 30, to spray water thereon. A branch, 36, extends upwardly from the union or section, 30, and passes through the under side of the hydraulic main, 37, where its upper open end terminates beneath a sealing bell, 38.

From the foregoing explanation it will be seen that the straight vertical portion, 21, of each standpipe is adjustably sustained 20 near its lower end and that each retort mouthpiece connected with a standpipe is also adjustably sustained so that the expansion and contraction of the standpipe and its connections with the retorts may be 25 cared for through said adjustments. By providing a slip joint at the upper end of the straight portion of the standpipe, the union or section, 30, may be rigidly secured without harm to the joint when the stand- 30 pipe does expand or contract.

Having thus described my invention what I claim and desire to secure by Letters Patent is:—

- 35 1. In an apparatus for the manufacture of coal gas the combination with a retort, of a stand pipe; a seal for one end of the stand pipe and means for adjusting the stand pipe in a longitudinal direction.
- 40 2. In an apparatus for the manufacture of coal gas the combination with a plurality of retorts, of stand pipes; connections between the retorts and stand pipes and adjustable means for sustaining the stand pipes.
- 45 3. In an apparatus for the manufacture of coal gas the combination with a retort mouth piece of a stand pipe having connections with the retort mouth piece; means for adjustably sustaining the mouth piece and means for adjustably sustaining the stand pipe.
- 50 4. In an apparatus for the manufacture of

coal gas the combination with a plurality of retorts each having a mouthpiece and arranged in vertical rows, of adjustable means interposed between the several mouthpieces 55 in a vertical row for bracing said mouthpieces; a standpipe for each vertical row of retorts said standpipe having a separate and independent connection with each retort and means for adjustably sustaining the stand- 60 pipes.

5. In an apparatus for the manufacture of coal gas the combination with a plurality of retorts each having a mouthpiece and arranged in vertical rows, of rotatable means 65 for adjustably bracing one mouthpiece from another; a standpipe for each vertical row of retorts and having an independent connection with each retort in the same vertical row and rotatable means for adjusting each 70 standpipe.

6. In an apparatus for the manufacture of coal gas the combination with a retort mouth piece; of a stand pipe having connection with the retort mouth piece; means for vertically adjusting the mouth piece with respect to the stand pipe; a hydraulic main; connection between the hydraulic main and stand pipe,—said connections having a slip joint with the stand pipe and means for adjustably sustaining the stand pipe. 75 80

7. In an apparatus for the manufacture of coal gas the combination with a plurality of disconnected retorts with mouthpieces arranged in vertical rows, of a standpipe extending vertically at one side of each vertical row of retort-mouthpieces and having a separate connection with each retort in the same vertical row; means for adjustably sustaining the standpipe and the mouthpieces 85 connected thereto; a hydraulic main; connections between the hydraulic main and the standpipe said connections including a slip joint with the standpipe, and means for rigidly securing said connections between the 90 95 slip joint and hydraulic main.

In testimony whereof I affix my signature in presence of two witnesses.

HOWARD BRUCE.
